DECORATIVE CHAIN FOR A
CHRISTMAS TREE

Jack Burnbaum, Newton, Mass.
(451 D St., Boston, Mass. 02127)

Filed Apr. 7, 1966, Ser. No. 1,801

Term of patent 14 years

(Cl. D29—1)

Fig. 1.

Fig. 2.

Fig. 3.

Fig. 4.

Fig. 5.

FIG. 1 is a top plan view of a decorative chain for a Christmas tree showing my new design,

FIG. 2 is a side elevational view,

FIG. 3 is a bottom plan view,

FIG. 4 is an end elevational view, and

FIG. 5 is an enlarged sectional view taken on the line 5—5 of FIG. 2.

The principal characteristic of my design lies in the union by integral stringing of the upper part of the bells with the flat beads, the bells being spaced apart by a uniform number of beads that are permanently connected thereto in the relationship shown.

I claim:

The ornamental design for a decorative chain for a Christmas tree, substantially as shown and described.
